United States Patent Office

Des. 187,582
Patented Apr. 5, 1960

187,582

TRACTOR

Charles R. Jefferson and Joe E. Fuzzell, Pekin, Ill., assignors to Caterpillar Tractor Co., Peoria, Ill., a corporation of California

Application April 22, 1959, Serial No. 55,618

Term of patent 14 years

(Cl. D14—3)

Des. 187,582

PAGE 2

FIG. 2

Fig. 1 is a view in side elevation of a tractor embodying our new design;

Fig. 2 is a perspective view of the same tractor;

Fig. 3 is a view in front elevation of the same tractor; and

Fig. 4 is a view in rear elevation of the same.

The essential features of our design reside in those portions shown in full lines.

We claim:

The ornamental design for a tractor, substantially as shown and described.
